UNITED STATES PATENT OFFICE.

ROBERT J. SCHEIDT, OF CALIFORNIA, MISSOURI.

AUTOMATIC BRAKE FOR ROAD-VEHICLES.

No. 882,210.

Specification of Letters Patent. Patented March 17, 1908.

Application filed August 20, 1906. Serial No. 331,310.

To all whom it may concern:

Be it known that I, ROBERT J. SCHEIDT, citizen of the United States, residing at California, in the county of Moniteau and State of Missouri, have invented certain new and useful Improvements in Automatic Brakes for Road-Vehicles, of which the following is a specification, reference being had therein to the accompanying drawing.

10 The object of my invention is to provide a novel construction of brake for road-vehicles, adapted to be automatically thrown into operative position through the medium of the horse or horses in going down hill, or 15 the like.

My device is at once simple of construction and inexpensive of manufacture, and thoroughly reliable and efficient in operation.

With this object in view, and others appearing as the specification proceeds, my invention comprehends the novel construction, combination, and arrangement of parts of a device characterized by my invention, as will be fully hereinafter described in the 25 specification, summed up in the claims, and illustrated in the drawings, in which latter:

Figure 1 is a top plan view of my brake-mechanism applied to a road-vehicle; Fig. 2 is a side elevation thereof; and Fig. 3 is a 30 side elevation of a slightly modified construction. Fig. 4 is a detail view.

Referring to the drawings, A designates the usual tongue of a road-vehicle, carrying at its forward end the customary neck-yoke 35 a, which is adapted for limited backward and forward movement on the tongue. Secured to the neck-yoke a is a connection a², its other or rear end being secured, as by a bolt a³, to a plate a⁴, provided with slots 40 a⁵, a⁶. Through these slots pass two bolts a⁶, a⁶, secured in the tongue A, thereby securing the plate against disconnection or removal from the tongue, and also at the same time limiting reciprocatory movement of 45 the plate on the tongue. Bolted at each end, as at a⁷, to the plate a⁴ may be a curved bar a⁸. Between the bar a⁸ and the plate a⁴ is positioned a double-tree a⁹ secured to the bar a⁸ and the plate a⁴ by a bolt a¹⁰; the 50 plate a⁴ and the double-tree a⁹ being thus incapable of movement together, but of no independent movement. Secured to the top of bolt a¹⁰ is a push-bar a¹¹, pivoted at its other end to a forked or bifurcated lever 55 a¹², fulcrumed, as at a¹³, to a rear tongue-

rod a¹⁴. The lower end of the lever a¹² is pivoted, as at a¹⁵, to a rod a¹⁶, whose other end is pivoted, as at a¹⁷, to a lever a¹⁸ fulcrumed to the reach a¹⁹. The other end of the lever a¹⁸ is pivoted to a forked rod, whose 60 arms or forks a¹⁹, a¹⁹ are secured to a brake-rod a²⁰.

The operation is apparent: Upon descending a hill, the horses draw back on the vehicle, exerting a backward pull or stress on the 65 neck-yoke a, which moves the connection a² rearward, carrying with it the slotted plate a⁴ and the double-tree a⁹. This backward movement of the double-tree throws the push-bar a¹¹ rearward, rocking the lever a¹² 70 on its fulcrum. This movement of the lever pulls the rod a¹⁶ forward, rocking the lever a¹⁸, and thus throwing the forks or arms a¹⁹, a¹⁹ rearward. The brake-rod a²⁰, being secured to the arms a¹⁹, a¹⁹, is consequently moved rearward, throwing the 75 brake-shoes firmly into contact with the wheels of the vehicle.

Should it be desired to back the vehicle on a level, I utilize a simple device to keep the 80 automatic brake-mechanism from operating: Slidably secured to the tongue A, near the bolt a³, are two loops of wire b, b, passing through eyes b² of a yoke b³. This yoke b³ is pulled over the bolt-head of the bolt a³ when 85 it is desired to back the vehicle on a level; this arrangement thus preventing the brake-mechanism from operating, as is apparent.

In Fig. 3, I have shown a slightly modified arrangement of the brake-mechanism: In 90 the device of this figure, the connection a² extends rearward to a point back of the double-tree a⁹, and this connection a² is slotted towards its rear end, bolts a⁶, a⁶ passing through the slots and into the tongue A, 95 as with the slotted plate a⁴ of Figs. 1 and 2. The remaining parts of the device of Fig. 3 are just the same as described in connection with Figs. 1 and 2. The only difference between the device of Fig. 3 and that of Figs. 100 1 and 2 is that, in the device of Fig. 3, the slotted plate a⁴ of Figs. 1 and 2 is omitted, and, instead, the connection a², itself, is extended back the distance which would otherwise be occupied by the said slotted plate, 105 and this connection a² is, itself, slotted, instead of the plate a⁴. As this is an obvious modification, I need dwell no further on it; but merely mention it because it may be considered by some as preferable, in simplifying 110

the construction of the device of Figs. 1 and 2, by omitting the element of the slotted plate.

It will be understood, of course, that any ordinary hand-brake may be used in connection with my automatic brake, without disturbance of any part of my automatic brake, or disturbance, by any part of my automatic brake, of the hand-brake. The use of a hand-brake with my automatic brake may be found efficacious, as, when desiring to leave a team, a driver may clamp the hand-brake in position.

From the above description, it will be noted that my brake-mechanism is simple of construction, not liable to get out of order, and thoroughly efficient in operation; and that it operates automatically whenever necessary, as on going down hill.

Having thus fully described my invention, what I claim as new and desire to secure by Letters Patent is:

In a road vehicle, a tongue, a neck-yoke sliding thereon, a plate having a sliding movement carried near the rear end of the tongue, a curved bar carried by the plate, a draft connecting means between the plate and bar, a bolt connecting the said means, plate and bar together, a push-bar connected to the upper end of said bolt, a brake mechanism, and means operably connecting the push-bar and brake mechanism.

In testimony whereof I affix my signature in presence of two witnesses.

ROBERT J. SCHEIDT.
